UNITED STATES PATENT OFFICE.

FRANK B. TWINING, OF TROY, NEW YORK, ASSIGNOR TO GEO. P. IDE & COMPANY, INC., OF TROY, NEW YORK, A CORPORATION OF NEW YORK.

MULTIPLY INTERWOVEN FABRIC FOR COLLARS AND CUFFS.

1,420,504.

Specification of Letters Patent. Patented June 20, 1922.

Application filed August 19, 1921. Serial No. 493,562.

To all whom it may concern:

Be it known that I, FRANK B. TWINING, a citizen of the United States, residing at Troy, in the county of Rensselaer and State of New York, have invented certain new and useful Improvements in Multiply Interwoven Fabric for Collars and Cuffs, of which the following is a specification.

It has heretofore been almost a universal custom to make collars, cuffs and the like of a plurality of separate plies which are stitched together only at their edges, so that the plies do not have the support of one another, except at the stitched edge portion, 15 the top edges of the neck band portion and fold over top portion being connected together in the vicinity of the folding line of the collar.

This method of manufacturing collars and 20 cuffs necessitates many handlings of the various separate plies and many rows of stitching. Consequently, there are numerous manufacturing operations incident to collars as heretofore made, each operation adding to the cost of the collar.

One of the objects of my invention is to 25 reduce the number of operations necessary to produce a collar.

A further object of my invention is to 30 produce a soft turn over collar from a single piece of multiply interwoven fabric of appropriate thickness and stiffness.

A further object of my invention is to produce a fabric from which soft fold over 35 collars may be made from a single thickness of multiply interwoven material of appropriate stiffness or thickness and having a narrow thickened cross sectional area on each side of the folding line of the collar extending 40 in the direction of the warp threads.

My invention consists of a multiply interwoven fabric for collars and cuffs having woven therein additional warp threads in a comparatively narrow zone, there being a 45 plurality of such zones spaced apart.

My invention consists further of a multiply interwoven fabric for collars and cuffs consisting of two panels connected integrally and having a comparatively narrow 50 portion with an increased number of warp

threads at parts which will be positioned in the completed collar at the top of the neck band and of the fold over top portion.

For the purpose of illustrating my invention, I have shown a portion of a woven 55 fabric with the different style collars indicated by dotted lines.

Figure 1 is a top plan view of a portion of a strip of fabric embodying my invention.

Fig. 2 is an enlarged detail sectional view 60 on the line 2—2, Figure 1.

The multiply interwoven fabric is woven accordingly to the regular textile now in vogue in weaving multiply interwoven fabrics, the only change in the weaving of the 65 fabric being that at predetermined points the operator introduces a greater number of warp threads for a predetermined width in the formation of the fabric whereby the cross sectional area of the fabric is increased 70 in thickness in the direction of the warp threads in two comparatively narrow zones, closely positioned relatively to each other so that after the collar is cut from my improved fabric the neck band portion "1," 75 of the collar will have a narrow strip "2" near its top thicker than the rest of the neck band and the fold over top portion "3" will have a relatively narrow thicker strip "4" at its top whereby the collar can be 80 readily folded in the zone between the two thickened portions, these thickened portions constituting or functioning as a guide for the proper fold of the collar. The fabric "5" may be woven any length or width and 85 the relative positioning of the group of two adjacent strips "2" and "4" can be arranged according to the style of collar to be cut therefrom, so that only the minimum amount of fabric is wasted in the cutting of the 90 collars.

I do not herein claim collars made from the fabric disclosed in this case, inasmuch as such collars constitute the subject matter of another application filed by me August 95 19, 1921, Serial No. 493,561.

What I claim is:

1. A multiply interwoven fabric for collars and cuffs having the warp threads increased in number in two spaced compara- 100

tively narrow adjacent zones in the fabric so that the increased warp threads constitute a guide for the fold line of the collar made from the fabric.

5. 2. A multiply interwoven fabric for collars and cuffs made up of a neck band and a top portion, each having a thickened inner

edge portion and an integrally woven portion extending between the thickened portions, said thickened inner edge portion defining the fold line.

In testimony whereof I affix my signature.

FRANK B. TWINING.
